UNITED STATES PATENT OFFICE.

OTTO L. OSTENDORF, OF MILWAUKEE, WISCONSIN.

CHAIR.

No. 900,301.

Specification of Letters Patent.

Patented Oct. 6, 1908.

Application filed March 21, 1903. Serial No. 148,957.

To all whom it may concern:

Be it known that I, OTTO L. OSTENDORF, residing at Milwaukee, in the county of Milwaukee and State of Wisconsin, have invented a new and useful Improvement in Chairs, of which the following is a description, reference being had to the accompanying drawings, which are a part of this specification.

This invention relates to chairs more particularly to improvements in that class of chairs known as "Morris chairs."

The object of this invention is to produce a chair of the class named having a seat or seat frame and a back or back frame independently adjustable to different inclinations.

A further object of this invention is to produce a chair as above outlined in which the front of the seat may be adjusted to different positions vertically of the chair body and in which the rear of the seat which supports the back frame, which is movable longitudinally of said seat, is supported by a seat supporting member adjustable vertically of the chair body, whereby when the desired inclination is given to the seat the back frame may be adjusted to different inclinations by the person using the chair while seated therein.

These, and other objects, I attain in the chair constructed as hereinafter described in the specification and illustrated in the drawings presented herewith in which

Figure 1 is a side elevation taken on a line inside of one of the side racks, of a chair embodying this invention; Fig. 2 is a rear view in elevation of said chair and in this view the back rail is broken away; Fig. 3 is a view looking toward the seat and taken on line 3—3 of Fig. 1; Figs. 4 and 5 are views in side elevation of said chair and illustrate different positions to which the back and seat may be adjusted.

Throughout the several views, similar elements are denoted by like characters.

In these illustrations I have shown a simple construction or design of a chair embodying this invention, the body of which consists of two side racks each having a rear post 6, front post 7, lower side rail 8 connecting said post, and a top or arm rail 9.

The side racks are connected by means of a front rail 10, and back rail 11.

Each rear post 6 is slotted, preferably as shown in Figs. 1 and 3 at 12 to form a series of engaging hook-shaped members which are adapted to support within the slots, the reduced ends 13 of seat supporting members

14 connected together by means of a stretcher or rod 15. In order to protect the edges of the series of slots formed in the rear posts against wear a metallic cap 12' is secured to the inner side of each rear post and said cap is slotted so as to correspond with the slots in the rear posts. 60

The lower ends of the seat supports 14 are formed in the nature of a hook 16 each adapted to engage a pin or peg 17 secured to the seat frame 18 adjacent to its rear end. By means of these series of engaging members the rear of the seat may be adjusted to and held in different positions vertically of the 70 chair body. The front posts 7 and the front rail 10 are connected together by means of angle irons 19 one wing of each of which is slotted as shown in Fig. 1 to form a series 20 of engaging slots adapted to receive and support a pin 21 secured to the forward end of the seat frame; and by this means the forward end of the seat frame may be adjusted to and held in different positions vertically of the 75 chair body. 80

The lower ends 22 of side arms 23 of the back frame, straddle the rear of the seat frame which is formed narrower than the front portion for that purpose and said lower ends of the side arms of the back 85 frame are provided with pins 24 which extend into slots 25 formed for that purpose in the seat frame. The back frame by means of pins 24 is supported by the seat frame and rests against the seat frame supports 14 as 90 a fulcrum. In order to move the back frame to and hold it in different positions each pin 24 outside of the side arms of the back frame carries a forwardly extending actuating member 26 provided with a slot 95 formed with a series of projections 27 for engagement with a pin 28 carried by the seat frame; the forward or outer end of each pin 28 is bent down as shown at 29 to hold the actuating member in place close to the 100 seat frame. As the tendency of the lower end of the back frame is to move forward, by means of the engaging projections 27 the back frame may be held in the desired position and by means of the actuating members which are provided at their forward ends with hand grasps 30, the back frame may be moved to different positions by the person using the chair while seated therein.

As shown in Fig. 5, if it is desired, a 110 stretcher 31 may be inserted within the slots above those carrying the seat supporters 14

and the back frame may rest against said stretcher instead of against the seat supporters whereby a separate adjustment of the back may be attained.

5 It will be understood that I do not limit this invention to the exact construction or design herein shown, neither do I limit it to any of the details of construction of the supporting or actuating members or slots.

10 What I claim as my invention is;

1. In a chair of the character described, a chair body, a seat frame at or near its forward end pivotally hung to said chair body, means for supporting the rear of said seat frame in different positions vertically of said body, a back frame supported by said seat frame, a member pivoted to the lower end of said back frame and provided with a series of engaging elements, and an agent on said seat frame with which said engaging elements are adapted to contact whereby said back frame may be moved to and held in different positions.

2. In a chair of the character described, a chair body, a seat frame pivotally connected at or near its forward end to said body, an agent pivotally connected to said seat frame for supporting the rear end of said seat frame in different positions vertical of said body, a back frame supported at its lower end by said seat frame and means for securing the lower end of said back frame to different positions along said seat frame.

3. In a chair of the character described, a chair body, a seat frame adjustably connected at its forward and rear ends to said body, an adjustable back frame supported by said body and said seat portion, a member pivotally connected to the lower end of said back frame and an agent carried by said seat frame and with which said member is adapted to engage whereby the lower end of said back frame may be moved to and held in different positions along said seat frame.

4. In a chair of the character described, a body portion, a seat frame pivoted at or near its forward end to said body portion, an agent pivotally connected to said seat frame and to said body portion for supporting the rear end of said seat frame in different positions vertical to said seat frame, a back

frame supported by said body portion and said seat frame and a member pivotally connected to the lower end of said back frame whereby the lower end of said back frame 55 may be moved longitudinally of said seat frame and held in different positions along it.

5. In a chair of the character described, a chair body, a seat frame pivotally hung at or near its forward end to said body, means for 60 supporting the rear end of said seat frame in different positions relative to said body, a back frame supported by said body and at its lower end by said seat frame, a member pivoted to the lower end of said back frame 65 and an agent on said seat frame with which said member is adapted to engage whereby said back frame may be moved to and held in different positions.

6. In a chair of the character described, a 70 chair body, a seat frame pivotally hung at or near its forward end to said body, means for supporting the rear end of said seat frame in different positions relative to said body, a back frame supported by said body and at 75 its lower end by said seat frame, a member pivoted to the lower end of said back frame and provided with a plurality of slots and a pin carried by said seat frame and adapted to engage one or another of the slots of said member whereby said seat frame may be moved to and held in different positions.

7. In a chair of the character described, a body, a seat frame pivotally hung and adjustably connected to said chair body at or 85 near its forward end, means for supporting the rear end of said seat frame in different positions relative to said body, an adjustable back frame supported by said body and at 90 its lower end by said seat frame, a member secured to said back frame and provided with a plurality of slots and a pin carried by said seat frame and adapted to engage one or another of the slots of said member whereby said back frame may be moved to and held 95 in different positions.

In testimony whereof, I affix my signature, in presence of two witnesses.

OTTO L. OSTENDORF.
